UNITED STATES PATENT OFFICE.

ANDREW C. DANVER, OF PAWTUCKET, RHODE ISLAND.

OILING SYSTEM.

1,200,172.

Specification of Letters Patent.

Patented Oct. 3, 1916.

Application filed April 18, 1916. Serial No. 92,039.

To all whom it may concern:

Be it known that I, ANDREW C. DANVER, a citizen of the United States, residing at Pawtucket, in the county of Providence and State of Rhode Island, have invented certain new and useful Improvements in Oiling Systems, of which the following is a specification.

My invention relates to an oiling system essentially adapted for use in that type of automobile wherein the oil depressions are located in the horizontal bottom of the crank case forward of the fly-wheel case.

The essential objects of my invention are to insure that when the vehicle is inclined toward the vertical, as in moving up an elevation, the forward oil pits or depressions shall not, as now, be deprived of oil by the flow of the latter to the fly-wheel case to such an extent that the cranks will not contact with the oil surface; to insure a single extensive and deep oil area to the cranks while the vehicle is moving on the level, which shall be immediately converted into a plurality of individual receptacles as soon as the vehicle reaches an incline; to maintain the same oil level at the center of crank splash on the grade as on the level; to return the superfluous oil to the fly-wheel case instead of to the first of the series of pits; and to attain these ends in a structure adapted for use upon an automobile without any substantial reconstruction.

To the above ends essentially my invention consists in such parts and combinations of parts as fall within the scope of the appended claims.

In the accompanying drawings which form a part of this specification, Figure 1 is a longitudinal section, partially in side elevation, of the crank case and adjacent parts of an automobile, Fig. 2, an enlarged central longitudinal section of the bottom of the crank case, Fig. 3, a plan elevation of the same, Fig. 4, a section on line 4—4 of Fig. 2, and Fig. 5, a view similar to that of Fig. 2, showing the position of the parts when the automobile is passing up an incline.

Like reference characters indicate like parts throughout the views.

In the drawings 6 is the crank case, 7 the fly-wheel case or oil reservoir, 8 the fly-wheel, 9 the magnets, 10 the crank shaft, 11 the cranks, 12 the crank case oil tube, and the adjacent parts of an automobile of the

Ford type, and it is in conjunction with these familiar parts that my invention is particularly adapted for use.

In detail my novel structure comprises a removable plate 15 adapted for attachment to the bottom of the crank casing in an opening 16 in the bottom thereof for the accommodation of the plate in front of the fly-wheel case. When attached in place this plate forms a portion of the crank case. The plate is oblong in outline and is provided with transversely disposed arcuate pits, pockets, or depressions 17 severally located immediately below and in vertical alinement with the cranks 11, and so disposed that the cranks in their rotation extend to a plane below the plane of the body of the plate.

Adjacent to each pit is a trough represented in a general way by the numeral 18. Each trough comprises a transversely disposed vertical back wall 19 spaced some distance to the rear of the rear of its pit and spaced at its ends from the lateral edges of the plate. Integral with the ends of this wall are inclined side walls 20, parallel with the lateral edges of the plate extending to points thereon forward of the adjacent pit thus partially inclosed thereby. These walls and the back wall are preferably cast in one piece with the plate. Around the margin of the plate is a wall formed in this instance by a frame or washer 21 provided at intervals with openings 22, to receive attaching screws or bolts 23 which pass through openings 24 in the crank case on which the washer rests, and through holes 25 in the margin of the plate 15.

It will be observed that between the walls 20 of the troughs and the wall 21 are formed resultant paths or channels 27 extending longitudinally of the plate 15.

When the automobile is moving on a level, the level of the oil over the area of the plate is usually the height of the wall 21, the oil being supplied in the usual manner by the crank oil tube 12 from the supply of oil 28 in the fly-wheel case. This level partially fills the pockets and partially fills the troughs.

When the automobile is passing up an elevation the parts assume the positions shown in Fig. 5, and a portion of the oil flows rearwardly through the channels 27 into the fly-wheel case, but the elevated troughs 18 retain a level of oil at their upper edges there-

by insuring a depth sufficient to immerse the margin of the crank under all circumstances. Two crank margins are so immersed in this figure.

5 I claim:—

1. In a crank case of the type set forth, the combination of a flat plate, a longitudinal series of transversely disposed pockets in the plate, and troughs upon the plate 10 spaced from the pockets and surrounding the pockets on three sides only.
2. In a crank case of the type set forth, the combination of a plate, a longitudinal series of transversely disposed pockets in the 15 plate, and longitudinally inclined troughs upon the plate surrounding the pockets on three sides.
3. In a crank case of the type set forth, the combination of a flat plate, a longitudinal series of transversely disposed pockets 20 in the plate, rectangular troughs on the plate surrounding three sides only of the pockets, and walls upon the plate parallel with and spaced from the sides of the trough.

4. In a crank case of the type set forth, 25 the combination of a flat plate, a longitudinally disposed series of transverse oil pockets in the plate, a vertical transversely disposed back wall on the plate in the rear of each pocket, longitudinally disposed side 30 walls on the plate at the ends of each back wall extending forward of the inclosed pocket and having their upper edges downwardly and forwardly inclined from the top of the back wall to the surface of the plate. 35

5. In a crank case of the type set forth, the combination of a flat plate, a longitudinally disposed series of oil pockets in the plate, a transverse wall on the plate in the rear of each pocket, inclined vertical side 40 walls on the plate extending from the top of the back wall to points forward of the pockets, and a marginal wall on the plate parallel with the side walls and spaced therefrom forming oil channels. 45

In testimony whereof I have affixed my signature.

ANDREW C. DANVER.
